UNITED STATES PATENT OFFICE

161,657

ASH TRAY

Franz Sojka, deceased, late of Vaduz, Liechtenstein, by Ada Sojka, executrix, Rochester, N. Y.

Application February 18, 1950, Serial No. 8,001

Term of patent 3½ years

(Cl. D85—2)

To all whom it may concern:

Be it known that Franz Sojka, deceased, late a citizen of Austria and resident of Vaduz, principality of Liechtenstein, has invented a new, original, and ornamental Design for an Ash Tray, of which the following is a specification, reference being had to the accompanying drawing, forming a part thereof.

Figure 1 is a top view of an ash tray, showing the new design.

Figure 2 is a side view thereof.

Figure 3 is a perspective view on a smaller scale.

What is claimed is:

The ornamental design for an ash tray, as shown.

ADA SOJKA.

*Executrix of the Last Will and Testament of
Franz Sojka, Deceased.*
